UNITED STATES PATENT OFFICE.

LEONIDAS BAXTER, OF DAYTON, OHIO, ASSIGNOR TO THE THOMAS MANUFACTURING COMPANY, OF DAYTON, OHIO, A CORPORATION OF OHIO.

SPRING-MOTOR.

1,315,456.

Specification of Letters Patent.

Patented Sept. 9, 1919.

Application filed October 24, 1917. Serial No. 198,283.

To all whom it may concern:

Be it known that I, LEONIDAS BAXTER, a citizen of the United States, residing at Dayton, in the county of Montgomery and State of Ohio, have invented certain new and useful Improvements in Spring-Motors, of which the following is a specification.

This invention relates to new and useful improvements in spring motors.

10 The principal object of my invention is to provide a combination speed regulator and brake for the motor, that is simple in construction and efficient in operation.

Another object of the invention is to provide a micrometer device for controlling the engagement between the worm on the governor shaft and the worm wheel on the turntable shaft, to insure a practically noiseless motor having increased efficiency.

20 Another object of the invention is the provision of an adjustable bearing for the turntable shaft.

And still another object of the invention is the provision of a micrometer device for regulating the end play of the governor shaft.

Other important and incidental objects will be brought out in the following specification, and particularly pointed out in the 30 subjoined claims.

The preferred form of embodiment of my invention is illustrated in the accompanying drawings, of which Figure 1 is a side elevational view of my improved spring 35 motor. Fig. 2 is a view, partly in section, of the micrometer device for regulating the engagement between the governor shaft worm and the turntable shaft worm wheel.

Fig. 3 is a view, partly in section, of the 40 micrometer device for controlling the end play of the governor shaft. Fig. 4 is a front view of one of my improved governor-arm supporting devices. Fig. 5 is an elevational view of the speed regulator and 45 brake for the motor. Fig. 6 is a side view of the brake-operating lever pivoted to the main motor frame. Fig. 7 is a side view of the forked operating arm adapted to be secured to said lever. Fig. 8 is a sectional 50 view of the adjustable bearing for the turntable shaft. Fig. 9 is a plan view of the split bushing for the latter. Fig. 10 is a side view thereof. Fig. 11 is a top plan 55 view of the motor cabinet, showing the speed-regulating device and brake control.

Fig. 12 is a side view of the speed regulator. Fig. 13 is a view thereof with the lower portion in section. And Fig. 14 is a sectional view on the line *a—a* of Fig. 13.

Throughout the specification and drawings, similar reference characters denote corresponding parts.

In a detailed description of the preferred form of embodiment of my invention, the numeral 1 designates the top, 2 the front wall, 3 the rear wall and 4 the bottom of the motor cabinet. Depending from the top 1 of the cabinet, is a supporting plate 5 having downwardly projecting portions 6, 7, 8 and 9 for supporting the motor parts. (See Fig. 1.)

Suitably journaled in the supporting structure just described is a spring motor 10 of the type described in my application Serial No. 163,795. This motor has a driving gear 11 which meshes with a pinion 12 on a transverse stub shaft 13. Fixedly secured to the other end of the stub shaft 13 is a bevel gear 14 in mesh with a bevel gear 15 on a vertical shaft 16 whose upper end 75 has a bearing in the plate 5 and whose lower end is journaled in a bearing in a flat member 17 secured to the downwardly extending portions 7 and 9 of the plate 5.

Fixed on the lower end of the shaft 16 85 is a gear 18 which meshes with a pinion 19 fast on the lower end of a turntable shaft 20. The lower end of this shaft is journaled in a bearing 21 secured to the member 17, its upper portion passing through an adjustable bearing in the plate 5, now to be described.

Referring to Fig. 8, the shaft 20 extends upwardly through a hole 22 in a boss 23 and the plate 5. Adapted to engage the lower end 24 of the boss 23, is an annular flange 25 on the shaft 20 to limit the upward movement of the latter. The hole 22 is threaded and enlarged a short distance above the lower end 24 of the boss 23 to receive a tapered and threaded split bushing 26.

The threaded bushing 26 and hole 22 taper downwardly for the following reason: Should the hole 22 be reamed too large or too small, or become larger by reason of wear, even to the extent of a thousandth of an inch, the shaft 20 may be accommodated to the increased or decreased diameter of the hole by screwing the bushing 26 downwardly 110

or upwardly the desired distance with a tool adapted to engage the recesses 27 27 therein. (See Figs. 9 and 10.) After the bushing 26 is adjusted to its desired position, a collar 5 cap 28 is inserted over a packing 28^a in an enlarged hole provided in the short boss 29 that extends upwardly from said plate 5.

Fast on the lower end of the shaft 20 is a worm wheel 30 which is adapted to be engaged by a worm 31 provided on a governor shaft 32. For the purpose of adjustably supporting the front end of the governor shaft 32 so that the worm 31 may be moved into and out of engagement with the worm wheel 30, the following device is provided:

Referring to Figs. 1 and 2, there is provided in the downwardly extending portion 7 a transverse groove 33 in which a bearing block 34 is laterally movable. This bearing block contains in its upper end a bore 35 terminating in a conical recessed inner end, and is adapted to receive a bushing 36 having a concaved inner end. Within the space between the concaved ends of the hole 35 and bushing 36 there is placed a ball bearing 37 which has a free movement therein and which is adapted to be engaged by the inner end of the governor shaft 32. (See Fig. 2.)

For the purpose of moving the bearing block within the recess 33 to carry the worm 31 toward and away from the worm wheel 30, there is provided a screw 38 that is adapted to be inserted in a socket 39 in the side face of the downwardly extending portion 7. Preferably integral with the screw 38, beyond its threaded portion, is a graduated collar 40 adapted to loosely enter an annular groove 41 that is provided in the bearing block 34 near its outer end. The collar 40 contains a series of peripheral graduations 42 whereby it may be turned a desired distance by a milled head 43 on the outer end of the screw 38, to adjust the engagement or mesh between the worm 31 and the worm wheel 30. After this engagement between the worm and worm wheel has been adjusted for a noiseless and efficient operation of the motor, the bearing block 34 may be held in its adjusted position by a screw 44 inserted into a hole therein, from the side of the downwardly extending portion 7. By the use of this micrometer device, it is thus possible to adjust the engagement between the worm wheel 30 and worm 31 to approximately a thousandth of an inch, for the purpose of securing a noiseless and easy running motor at all times.

Longitudinally movable on the shaft 32 beyond the worm 31, is a brake disk 45. Preferably integral with the inner middle portion of the disk 45 is a boss 46 having an upwardly flaring or bell shaped rim 47. (See Figs. 1 and 4.) Suitably secured to that portion of the boss 46 that is of least diameter, are preferably three centrifugal

arms 48 whose opposite ends are secured to a bell shaped element similar to the boss 46. Suitably secured to the middle portion of each of the arms 48 is a centrifugal weight 50.

Referring to Figs. 3 and 4, there is provided in the flaring portion 47 of the boss 46, and in the flaring portion 51 of the element 49 a slot 52 for each of the centrifugal arms 48. These slots 52 are provided so that the arms 48 may extend through them in an approximately straight line as shown in Figs. 1 and 3, when the motor is not running or running slow, and to restrain their outward movement beyond a danger point 70 when the motor is operating at great speed. During their expanding period, the arms 48 cannot be moved by the weights beyond the ends of the slots 52 through which they extend, and these ends are positioned a sufficient distance from the edge of the flaring rim of the arm support to prevent said arms from overexpansion or contact with other parts to their injury. The centrifugal arm supporting elements 46 and 49 are connected together by a telescopic sleeve 53 through which the governor shaft 32 passes.

For the purpose of adjusting the end thrust of the shaft 32, the following device is provided: Referring to Fig. 3, the numeral 54 designates a bearing member which is movable through a transverse hole provided in the downwardly extending portion 8 of the plate 5. The bearing member 54 is preferably cylindrical in cross section, and contains in its front end a bore 55 that receives a bushing 56 having a concaved inner end. The opposite end of the bore 55 is also concaved to provide between the inner end of the bushing and the inner end of the bore 105 a space for the free movement of a ball-bearing 57 which the inner end of the shaft 32 is adapted to engage.

For the purpose of insuring a proper engagement between the ends of the shaft 32 and the ball bearings 37 and 57, the bearing member 54 may be moved in either direction by a screw 58 which enters a threaded bore 59 that transversely passes through the downwardly extending portion 8 of the 110 plate 5. This screw has an annular graduated collar 60 which loosely enters an annular groove 61 provided in the outer end of the bearing member 54. Accordingly, when the milled head 62 on the outer end of the 115 screw 58 is turned, the bearing member 54 will be given a longitudinal movement by the annular collar 60. Furthermore, the collar 60 has peripheral graduations 63 whereby the shaft may be longitudinally adjusted to the bearings 37 and 57, to approximately a thousandth of an inch with accuracy, and is held in its adjusted position by a screw 63^a.

In order to regulate the speed at which 120

the talking machine record rotates, and to stop the latter completely when desired, the disk 45 is adapted to be engaged by two friction pieces 64, one on each side of the 5 boss 46. (See Figs. 1 and 5.) Each friction piece 64 is carried by the lower end of an arm 65. These arms 65 are connected by an integral cross piece 66 which is preferably secured by a rivet 67 to an inwardly extending portion 68 of a lever 69 that is pivotally secured by a screw 70 to the side portion 71 of the plate 5. The lever 69 has a rearwardly extending portion 72 from the lower edge of which there projects outwardly 10 a tongue 73. (See Figs. 1, 5 and 6.) Upon this tongue rests the lower end of a vertically and rotatably movable element 74 which extends loosely through the vertical sleeve portion 75 of a bracket 76 secured to the top face of the plate 5. Referring to Fig. 5, the front lower side of the sleeve portion 75 is formed to slope downwardly and inwardly to provide a cam surface which a pin 77 projecting outwardly from the lower 15 end of the element 74, is adapted to engage.

When the element 74 is turned clockwise, it will be forced downwardly through the engagement of its pin 77 with the sloping surface of the sleeve 75. During its downward movement, the element 74 will press against the tongue 73 with sufficient force to cause the lever 69 which carries the latter, to bring the friction pieces 64 into sufficiently tight engagement with the disk 45 20 to stop the motor, and when this point is reached, the pin 77 will have lodged in a slight recess 78 in the curved surface of the sleeve 75, to be held there for the purpose of preventing the motor from running until 25 it is again desired to start it.

For the purpose of enabling this brake device to be conveniently operated by the user of the machine, the element 74 extends a sufficient distance above the top 1 of the cabinet to fixedly receive one end of an arm 45 79. To the other end of said arm there is attached a knob 80 whereby it may be readily moved by the operator to turn the element 74 for the purpose of starting or stopping the motor. The movement of the arm 79 is limited in each direction by screws 81 50 which are connected by a flat piece 82 beneath which said arm is operable. (See Figs. 1 and 11.)

55 In order to combine the brake just described with a speed-regulating device for the motor, the following construction is provided. Referring to Figs. 1, 11, 12, 13 and 14, there is provided on the top 1 of the cabinet a speed-indicating dial 83. This dial, which contains a large number of graduations 84, is preferably secured to the cabinet top 1 by means of screws 85. Fixedly secured within an aperture in the middle 60 portion of the dial 83 is a sleeve 86 which

extends downwardly therefrom through the cabinet top 1.

Extending through the sleeve 86 and dial 83 is an adjusting element 87, to the upper end of which a pointer 88 and knurled knob 89 are fixedly secured, the pointer being disposed so that its outer end may register with the graduations 84 on the dial 83. Applied to the sleeve 86 for a vertical and rotatable movement thereon, is a slotted sleeve 90 70 whose lower end is tapered to tightly receive a downwardly projecting pin 91.

In one side of the sleeve 90 a straight slot 92 is provided, said slot extending from the upper middle portion of said sleeve downwardly to its tapered portion. (See Fig. 12.) Opposite the slot 92, and extending from a point near its lower end to a point a short distance above its upper end, is a spiral slot 93 into which loosely extends a pin 94 secured to the sleeve 86. From the lower end of the adjusting element 87 there loosely extends into the straight slot 92, a pin 95. Accordingly, when the knurled knob 89 is turned, the pin 95 will be rotated by the 90 adjusting element 87 to which said knob is secured, to turn the slotted sleeve 90. But this sleeve 90 also contains a spiral slot 93 into which the fixed pin 94 extends from the sleeve 86. Therefore, when the knob 89 is 95 turned, the slotted sleeve will be given a vertical movement through the engagement of its spiral slot 93 with the fixed pin 94, to raise and lower the pin 91 for a purpose now to be described.

Referring to Figs. 1 and 7, the numeral 96 designates a forked piece, whose forked end is adapted to receive a screw 97 secured to the rear end of the lever 69. Pivotally secured to a screw 98 secured to the rear portion of the plate 5, is one end of a lever arm 99 which extends outwardly a sufficient distance to bring the slot 100 in its outer end to a position to loosely receive the pin 91 secured to the sleeve 90. The forked piece 96 105 has a reduced end 101 which is adapted to loosely extend through an aperture in the middle portion of the lever arm 99. A coil spring 102 secured to the shank of the screw 98 normally exerts its force against the inner end of the lever arm 99 to raise the latter, and with it the reduced end 101 of the forked piece 96, which in turn actuates the lever 69 to hold the friction pieces 64 out of engagement with the disk 45.

However, by turning the knob 89 to a position wherein the pointer 88 will register with a graduation on the dial 83 indicating a desired motor speed, the sleeve 90 will be lowered to a position to restrain the upward 115 movement of the spring-pressed lever arm 99 at a point where the friction pieces 64 will engage the disk 45 with sufficient force to give that speed. Therefore, it will be seen that by turning the knob 89 to bring the 120 125 130

pointer 88 to a desired graduation on the dial 83, the sleeve 90 will be raised or lowered a sufficient distance to restrain the upward movement of the lever arm 99 at a point where the friction pieces 64 will tightly or lightly engage the disk 45 to permit the motor to run at the speed indicated on the dial. Furthermore, if it is desired to stop the motor completely, it is only necessary to move the arm 79 as before described, which will, independently of the speed-regulating mechanism, cause the element 74 to press the tongue 73 downwardly a sufficient distance to accomplish that result. It will thus be seen that I have provided a combination brake and speed-regulating mechanism which is easily operated and efficient.

I do not wish to be limited to the details of construction and arrangement herein shown and described, and any changes or modifications may be made therein within the scope of the subjoined claims.

Having described my invention, I claim:

1. In a spring motor, the combination with a governor shaft, a support therefor, a worm on said shaft, a bearing in one part of said support for one end of said shaft, a driving worm wheel adapted to be engaged by said worm, of a bearing block transversely movable in said support to receive the other end of said shaft, and a micrometer device adapted to laterally shift the bearing block a desired distance to adjust the engagement between said worm and worm wheel.
2. In a spring motor, the combination with a governor shaft, a support therefor, a bearing mounted in one part of said support for one end of said shaft, a worm on said shaft, a driving worm wheel which said worm is adapted to engage, of a bearing block slideable in a recess provided in a flat portion of said support, to receive the other end of said shaft, a screw insertible in said support in alinement with said bearing block, a head for said screw, a graduated annular collar on the latter adapted to loosely enter an annular groove in said bearing member to move it longitudinally for the purpose of adjusting the end thrust of the governor shaft, and a second screw adapted to be passed into the bearing member from the support to hold it in its adjusted position.

the engagement between the worm and worm wheel when the head of the screw is turned, and a second screw adapted to be passed into the bearing block from the support to hold it in its adjusted position.

3. In a spring motor, the combination with a governor shaft, a bearing piece for each end of said shaft having a bore whose inner end is tapering, of a bushing insertible in each bore to receive its respective end of said shaft, each bushing having a concaved inner end, and a ball bearing having a free movement in the space between the inner end of the bore and its respective bushing to receive the end thrust of its respective end of the governor shaft.

4. In a spring motor, the combination with a governor shaft, a support therefor, a bearing in one part of said support for one end of said shaft, of a bearing for the other end of said shaft, movable in the direction of the length of the latter through another part of said support, and a micrometer device adapted to longitudinally shift the bearing member a desired distance to adjust the end thrust of the shaft.

5. In a spring motor, the combination with a governor shaft, a support therefor, a bearing in one part of said support for one end of said shaft, of a bearing member slideable through another part of said support in the direction of the length of said shaft, to receive the other end of the latter, a screw insertible in said support in alinement with said bearing member, a head for said screw, a graduated annular collar on the latter adapted to loosely enter an annular groove in said bearing member to move it longitudinally for the purpose of adjusting the end thrust of the governor shaft, and a second screw adapted to be passed into the bearing member from the support to hold it in its adjusted position.

In testimony whereof I have hereunto set my hand.

LEONIDAS BAXTER.
